UNITED STATES PATENT OFFICE.

PHILIP S. CHESS, OF PITTSBURGH, PENNSYLVANIA.

PACKAGE.

1,312,611.

Specification of Letters Patent.

Patented Aug. 12, 1919.

Application filed May 7, 1919. Serial No. 295,395.

To all whom it may concern:

Be it known that I, PHILIP S. CHESS, residing at Pittsburgh, in the county of Allegheny and State of Pennsylvania, a citizen of the United States, have invented or discovered certain new and useful Improvements in Packages, of which improvement the following is a specification.

My invention relates to packages which, 10 while suitable for handling, transportation, etc., still display the contained goods, and display them in informing and attractive manner. It is not necessarily so limited, but finds its more obvious application in 15 packages containing liquid or partly liquid or soft substances. I shall describe the invention as applied in marketing groceries.

Such groceries as preserved fruits, for example, jellies, fruit juices, vegetables, vinegar, olive oil, honey, and even cheese and meat, are commonly marketed in glass containers (bottles, jars, and the like), for glass is cheap, and the display of the goods themselves through the transparent container 25 walls aids in their sale. The bottles, jars, etc., ordinarily bear labels, to indicate the nature of the contents, the name of the producer or vendor, and sometimes other matters. It is common to place upon the label 30 pictorial representation of the goods themselves, or of the fruit or other article from which the goods are prepared. It is to such pictorial representation upon the label which the container bears that my invention connects itself. The picture upon the label is 35 so displayed and arranged that the goods themselves, seen through the transparent container wall, shall enter into, and by form, or color, or both, complete the presentation borne incompletely upon the label itself.

The invention is illustrated in the accompanying drawings. They are not by any means exhaustive of the possibilities, but 45 they are sufficiently illustrative and suggestive. The several figures show, in side elevation, packages to which the invention is applied.

Figure 1, by way of example, shows a 50 bottle of grape-juice; Fig. 2 a jar of preserved cherries; Fig. 3 a jar of jam; and

Fig. 4 a bottle of syrup. The label which the grape-juice bottle (Fig. 1) bears is adorned with the pictorial representation of a bunch of grapes. Part (preferably the 55 marginal part, as shown) of the cluster of grapes is depicted on the label; but, over the medial portion, the label is cut away, so that, when the bottle is filled, the color of the grape-juice within enters into the pictorial representation. Each portion of the cluster as thus represented enhances the attractiveness of the whole; the artificial outline and color of the grapes on the printed label give what the otherwise monotonous 60 display of the liquid within alone would fail to give, while even the slight translucence of the grape-juice seen through glass affords a richness which printed paper alone could not supply. The quality of translucence here alluded to becomes a much more 65 notable feature in the case of other articles—honey, for example, or maple syrup. It will be observed, too, that this cut-away area, this look-hole through the label, is advantageously arranged at that very portion of the fair area of the bottle's surface through which the contents may most advantageously 70 be seen. At the same time, the over-all dimensions of the label are as great as may be, 75 and the area for the display of lettering is not disadvantageously encroached upon.

In the case of the cherry-bottle of Fig. 2, it is not the color and translucence alone of the contents which enters into the design, 85 but the form too. The label bears the pictorial representation of the stem of a cherry tree, with its leaves and fruit. Part of the fruit itself is preferably depicted in the label (though there is not in this case the 90 same necessity to supply representation of the form of the fruit) while for the rest, it is the fruit within the jar, seen through a properly shaped opening in the label, which completes the picture. Again, the pictured 95 cherry stem enhances the attractiveness of the fruit, while the form, color, and translucence of the fruit within adds to the attractiveness of the picture. The feature of novelty too and distinctiveness is not lacking 100 in advertising value.

Fine fruits nowadays are most carefully

placed within jars, and peaches and plums may thus be brought to give their luscious color to pictorial labels. In like manner olives may be treated, tomatoes, asparagus, 5 and other fruits and vegetables.

Fig. 3 shows a jar of jelly, and (by way of suggestion) the picture there displayed is of a slice of bread, partly spread. The still unspread lump of jelly upon the bread is 10 represented, not in print, but in the color of the jelly itself seen through an opening in the label.

Fig. 4 shows a bottle of syrup. The label does not in this instance cover the whole face 15 of the bottle, nor is it interrupted in its extent with an opening or look hole. It does not reach to the bottom of the bottle. The label bears a picture of a plate of hot cakes over which syrup has been poured and from 20 which the syrup flows in a pictured stream which merges in the pool formed by the syrup itself within the bottle, exposed below the lower edge of the label.

In each of these instances there is a combination 25 of materials such as an artist may employ, to produce unusual and most inviting pictorial effects.

It will be understood that in displaying goods dressed for the market according to 30 my invention, clever lighting arrangements may be resorted to and most attractive effects produced of the goods ranged on shelves or stands or in store windows.

If, as shown in Fig. 1-3, there be a look-hole in the label, this look-hole will preferably be an actual aperture—simply an open space. On the other hand, this space may be filled with a transparent inlay, making the 40 label physically continuous. Again, the paper of the label may be a continuous sheet, by suitable treatment rendered transparent over the desired area. Such alternatives are included in the term look-hole and generally in the phrasing of this specification.

The label need not be a separate entity, as 45 of paper, pasted to the container; it may in proper case be formed in or on the substance of the container by such operations as molding, etching, sand-blasting, applying molten 50 glass or other plastic—the color being supplied by painting or by permeation of an applied plastic, or otherwise. The term label in the ensuing claims includes all such formations.

In the sale of groceries, the size of the container is not great—ordinarily it does not exceed a quart in capacity—and the superficial area is accordingly limited. The goods are ordinarily ranged on the shelves of stores, 60 and, when so arranged, a few square inches (and only a few) of the surface of each container are exposed to view. There are two desiderata; one, that the labels be of sufficient size, and the characters borne by the labels of 65 sufficient size, to be legible—intelligible—to

one standing at a distance—on the floor of a grocery store, for example, and looking at bottles ranged on a shelf against the wall and behind a counter; or, again, to one standing on a sidewalk, and looking through a window at articles displayed within. The other desideratum is that the transparent containers shall display the contents and attract attention and interest, by color, translucence, and appearance generally. But, because of the limitations of dimension already alluded to, labels of size sufficient to serve best as labels, so far conceal the contents that ordinarily, if visible at all, they are to be seen only through bottle necks and 70 rounded and refracting sides and corners or jars, and where perhaps the color of the glass spoils the desired appearance. It is common enough for the salesman in such stores to be obliged to turn their backs in 75 order to reach to shelves and turn bottles and jars around, that the contents may be displayed to customers. In a word, the difficulty is at once to mark the goods adequately and to display the goods through 80 their transparent containers. It will be apparent that in the practice of my invention the goods may be displayed to best advantage and at the same time the maximum area 85 of label may be had for the display of desired or necessary wording, etc.

I have in the foregoing explanation laid emphasis on food and drink products. It is with them that the invention has particularly manifest application. But it is applicable 100 too, as will readily be perceived, to toilet preparations, paints, etc., and even to museum specimens, in which case there is a simple matter of display not involving the marketing of goods. In such regard my invention is not limited in applicability. I have throughout described the container as made of glass. Ordinarily, such will be the case; but, manifestly, any transparent container is susceptible to application of my invention.

I claim as my invention:

1. A package comprising a transparent container bearing a label, the label bearing pictorial representation of a colored object, 115 and consisting further of material within the container, the color of the object depicted in the representation upon the label being borne in part upon the label and in part supplied by the material within the container, displayed through the transparent 120 container wall.

2. A package containing an article of distinctive form, and comprising a transparent container, a label borne by said container 125 and bearing pictorial representation of the recognized surroundings of the article contained within, and consisting further of an article within the container, visible through the transparent wall thereof, and supplying 130

to the pictorial representation upon the label a presentment of the article itself, completing the picture.

3. A vendible package of preserved fruit, 5 comprising a transparent container, a label borne by said container and bearing pictorial representation of a stem of the plant which produces the fruit in question, and 10 consisting further of fruit within the container, visible through the transparent wall

thereof, and by position shape and color completing the picture delineated on the label.

In testimony whereof I have hereunto set my hand.

PHILIP S. CHESS.
